UNITED STATES PATENT OFFICE.

CHARLES H. WHITE, OF BOSTON, MASSACHUSETTS.

RAILWAY-SWITCH.

SPECIFICATION forming part of Letters Patent No. 268,761, dated December 5, 1882.

Application filed May 24, 1882. (No model.)

To all whom it may concern:

Be it known that I, CHARLES H. WHITE, of Boston, county of Suffolk, State of Massachusetts, have invented an Improvement in Railway-Switches, of which the following description, in connection with the accompanying drawings, is a specification.

My invention relates to railway-switches, and is embodied in a switch that is automatically operated by the approaching train, so as to be placed in line with the branch from which the train is moving, regardless of the position the said switch may be in before the train reaches it, and also to enable the engineer of a train approaching the branching portion of the road to cause the switch to be set so as to direct the train onto either branch as may be desired. At the switch or place where a single line of rails approaching from one side is to be connected with either of two lines branching from the other side, the rail on one side of the said single line is made continuous with the corresponding rail of one of the branches, which may for convenience be called the "main line," and the rail at the other side is made continuous with the other branch or siding. The rail of each branch on the same side with the continuous rail of the other branch terminates at a sufficient distance from the said continuous rail to permit the passage of the flanges of the wheels when moving on the continuous rail. The movable portion of the switch consists of two points connected rigidly with a frame-work having a sliding movement transverse to the track, by which one or the other of the said points is placed against the adjacent continuous rail where it forms a connection and guide for the wheel-flange from the said continuous to the discontinuous rail, while the point on the other side of the track is removed a sufficient distance from the adjacent continuous rail to permit the passage of the wheel-flanges, for which it also serves as a guide. One of the said points thus acts on the flanges of the outside or tread side, and the other point acts on the inside of the wheel-flanges, and each wheel of each pair is thus independently guided to the proper branch, and the tendency of the wheels in passing is to retain the points in the position they are set, so that it is impossible for a pair of wheels to leave the branch upon which the preceding

wheels have passed. Automatic switch-operating levers are employed in conjunction with each of the discontinuous rails, respectively, 55 they being connected with the movable points and operated by the flanges of the wheels approaching from either branch to place the said points in proper position to connect the discontinuous rail forming a part of the said 60 branch with the continuous rail on the same side of the track. Levers similarly connected with the movable points are employed at either side of the single portion of the track, either lever being operated by a suitable device controlled by the engineer of the approaching train to move the points so as to guide the 65 wheels to the corresponding branch.

The invention further consists in the mechanism by which the movable points are operated in order to direct the vehicles to the different branches, as desired, the said mechanism being such that when locked it prevents tampering with the switch to change the position of the points, although it leaves the said 75 points free to be moved automatically by the approaching trains.

I am aware that switches have been devised for automatical operation of trains approaching in either direction, and I do not broadly 80 claim mechanism for accomplishing this result.

Figure 1 shows in plan view a portion of a railway having a switch embodying this invention. Fig. 2 is a longitudinal section thereof, in section, on line xx , Fig. 1; Figs. 3, 4, and 5, 85 transverse sections on lines yy , zz , and $x'x'$ of Fig. 1, respectively; Fig. 6, a side elevation of the stand containing the switch-operating mechanism; Fig. 7, a plan view, and Figs. 8 and 9 details thereof.

The rails a a' of the single or unbranched portion of the track are made continuous, one to each branch, while the rail b' of the one branch or siding approaches the rail a , as shown, as nearly as consistent with sufficient space 95 for the flanges of the wheels passing over the rails a and then terminates, and the rail b of the other branch or main track is similarly arranged with relation to the continuous rail a' of the siding. This arrangement of the rails, 100 however, forms no part of the present invention. The ends of the discontinuous rails b b' are tapered in the usual manner, and bed-blocks c d are fitted at either side of the web

thereof, and with the said tapered ends are securely fastened to the continuous rails by means of the clamps *e*, having one end fitted over the flange of the said continuous rail 5 and its other end provided with a key-seat for the key or wedge *f*, acting between the said seat and the shouldered face of the bed-block *c*, as shown in Fig. 5.

The movable portion of the switch, by which 10 the vehicles may be directed from the rails *a* *a'* upon either branch *a b* or *a' b'*, as desired, consists of the two points *g g'*, rigidly connected together from end to end, as by the cross-bars *h*, thus forming a frame-work adapted to slide 15 transversely to the track *a a'* upon a bed-plate, *i*. (See Fig. 4.) The said points each have one side parallel with the adjacent continuous rail and their other side parallel with the opposite continuous rail, and when moved so 20 that one of the points, as *g'*, is in contact with the adjacent continuous rail, *a'*, the other side of the said point is in line with the discontinuous rail *b*, the said point thus forming a connecting-piece between the rails *a'* and *b* for the 25 tread and flanges of the wheels parallel with the opposite continuous rail, *a*, so that the wheels are guided to the branch *a b*. When the point *g'* is in contact with the rail *a'* the opposite point, *g*, is removed from the rail *a* a sufficient distance to permit the wheel-flanges 30 to pass between the said rail and the point, which thus serves as a guide or guard rail to prevent the wheel-flanges from passing from the rail *a* onto the rail *b'*. When the connected points are moved transversely to the 35 track in the direction of the arrow 2 the point *g* is brought in contact with the rail *a*, forming a connection therefrom to the rail *b'*, while the point *g'* serves as a guide for the flanges 40 of the wheels passing along the rail *a'*, so that the wheels are guided to the branch *a' b'*. Guard-rails *j*, at either side of the unbranched portion *a a'* of the track, guide the wheel-flanges to the proper side of the points, and 45 the latter then guide them to the proper side of the discontinuous rails *b b'*, so that even if a wheel is loose upon its axle it is impossible for it to leave the proper rail at the switch. It will be seen that the connected points have a 50 sliding movement at both ends and throughout their entire length, and that in either position one of the said points rests in contact throughout its entire length with one of the fixed continuous rails, so that the switch has as rigid a connection with the sleepers and is 55 in every way as firm as any portion of the track. The points are moved to direct the vehicles to the different branches by the bar *k*, provided with a socket to receive a stud, *l*, 60 fixed upon the target-shaft *m*, (see Figs. 7 and 8,) so that by the quarter-rotation of the latter the bar *k* is moved longitudinally, it yielding laterally by its elasticity sufficiently to conform to the curvilinear movement of the 65 stud *l*. A fixed stud, *n'*, limits the lateral yielding of the bar *k*, which is provided with

recesses 3, as shown, to receive the shaft *m* at the end of its movement. The shaft *m* is provided with a target, *m'*, (see Figs. 1 and 4,) which, by its quarter-rotation, is made to present its face or its edge to be viewed from an approaching train to thus indicate the position of the switch. The shaft *m* is rotated to shift the points by a lever, *n*, pivoted thereto, as shown in Fig. 9, so that it may be turned 70 at right angles to the shaft in order to rotate it or may hang down at the side thereof, as shown in full lines.

In order to lock the switch so as to prevent its being tampered with and yet permit it to be 80 automatically operated by the train, as hereinafter described, the said shaft *m* and lever *n*, when hanging down, as shown in full lines, Fig. 9, are inclosed in a housing or stand, *o*, Fig. 6, provided with a door, *o'*, of sufficient 85 width to permit the lever *n* to be raised when in any position assumed by it in the movement of the points. The door *o'* is provided with a lock, *o''*, to prevent access of unauthorized persons to the lever *n*, so that after the switch is 90 once set and the lever *n* locked in the stand *o*, such persons will be powerless to shift the switch. An opening, 9, is left above the door *o'*, sufficient to permit the lever *n* to extend out therethrough, so that the door may be 95 closed without dropping the lever *n* when it is desired to shift the switch frequently for a considerable length of time without locking it. It will be seen that the tendency of the wheels 100 passing over the points is to retain them in the proper position, instead of to move them therefrom.

The point-moving bar *k* is also connected with a lever, *p*, pivoted at 4, and connected with a cross-bar or link, *r*, (see Fig. 5,) connected with levers *s s'*, pivoted at 5 in position to be acted upon by the flanges of the wheels passing over the discontinuous rails *b b'* of the two branches of the track. The said wheel-flanges in passing over either of the said rails 110 *b* or *b'*, in moving toward the rear end of the points, force the corresponding lever, *s* or *s'*, away from the said rail, (if not already removed therefrom,) and thus through the link *r*, lever *p*, and rod *k*, place the points in proper position to connect the said discontinuous rail with the corresponding continuous rail and to cause the vehicles to pass properly from the branch to the single or unbranched portion of the track. As shown in Fig. 1 the points are in 115 position for a train to pass from the branch *a b* to the line *a a'*, and the lever *s* will not be moved by the train passing from the said branch, as it is already a sufficient distance from said rail. If, however, a train should 120 move in the direction of the arrow 6 over the branch *a' b'*, the flanges would force the lever *s'* away from the rail *b'*, and thus, through the link *r*, lever *p*, and bar *k*, will move the points in the direction of the arrow 2 into proper position for the wheels to pass from the branch *a' b'* to the line *a a'*. It will be seen that the 125 130

points are thus automatically set in proper position by a train moving in the direction of the arrow 6 over either branch $a b$ or $a' b'$.

The bar k is also connected with a lever, t , connected with a cross-bar, u , having attached thereto levers $v v'$ at the outside of the main rails $a' a$, so as not to be affected by the wheels passing over the said rails.

Projections or tappet-arms $w w'$, (see Fig. 3,) carried by the locomotive in advance of the wheels, may be thrust down independently by the engineer, so as to pass along the outer edge of the corresponding rail, and, entering between it and the corresponding lever, force the latter outward from the rail, and thus move the points to direct the train upon either branch, as desired, according as one or the other of the said arms is depressed. As shown in Fig. 3 the arm w is depressed, thus acting on the lever v and throwing or retaining the points in position for the main line $a b$. If the arm w' were depressed, it would force the lever v' away from the rail a' , and thus through the intermediate connection move the points in the direction of the arrow 2, causing them to guide the train onto the branch $a' b'$.

I am aware that points or switch-rails have been actuated by the wheels or projections carried by trains acting upon levers connected by intermediate mechanism with the movable points or rails.

I claim—

1. In a railway-switch, the continuous rails and discontinuous rails of the single main track and branches, arranged as described, combined with the two points $g g'$, and their rigid point-supporting frame-work having a sliding movement at both ends and throughout its length transverse to the track, substantially as and for the purpose set forth.

2. The combination, with the single track and tracks branching therefrom, of the points $g g'$ and the rigid point-supporting frame-work therefor, having a sliding movement at both

ends and throughout its entire length, and the connected point-operating levers $s s'$, actuated by the wheels passing over each branch, and the intermediate lever p , connected with the said levers $s s'$ and with the rigid point-supporting frame-work, substantially as and for the purpose described.

3. The combination, with the single track and tracks branching therefrom, of the points $g g'$ and the rigid point-supporting frame-work therefor, having a sliding movement at both ends and throughout its entire length, and the connected point-operating levers $v v'$, located at either side of the single portion of the track, and the intermediate lever t , connected with the said levers $v v'$ and with the point-supporting frame-work, substantially as described.

4. The movable points and their actuating-bar and levers adapted to be operated by the passing trains, combined with the target-shaft, lever pivoted thereto, and housing adapted to receive the said shaft and lever when parallel with one another, substantially as described.

5. The movable points and point-supporting frame and the bar k , connected therewith, and the intermediate levers, $p t$, connected with the said bar and with links transverse to the track, combined with automatic actuating-levers $s s'$, connected with one of the said links and located at the flange-guiding side of a rail of each branch, and the actuating-levers $v v'$, connected with the other of the said links, and located at the outside of each rail of the single portion of the track, all the said levers operating in planes substantially parallel with the road-bed, substantially as described.

In testimony whereof I have signed my name to this specification in the presence of two subscribing witnesses.

CHARLES H. WHITE.
